UNITED STATES PATENT OFFICE.

HARRY F. JOSEPH, OF DAVENPORT, IOWA, ASSIGNOR, BY MESNE ASSIGNMENTS, TO
MICRO MACHINE COMPANY, OF BETTENDORF, IOWA, A CORPORATION OF IOWA.

GRINDING MACHINE.

Original application filed August 7, 1920, Serial No. 401,988, Patent No. 1,396,123, dated November 8, 1921. Divided and this application filed October 8, 1921. Serial No. 506,300.

This invention relates to grinding machines, and particularly to machines for grinding the inner or outer faces of automobile cylinders, pistons, pins, valves, and in fact, all parts commonly found on automobiles, though it is obvious the invention is not limited to the use for which it is particularly designed, as it might be used for grinding cylinders or other parts for other mechanisms.

The general object of the invention is to provide a mechanism of this character including a grinding wheel which is rotatable and at the same time may be moved in a circle around the central longitudinal axis of revolution or may be rotated without moving bodily around the central axis.

A further object in this connection is to provide means whereby the feed of the grinding wheel may be controlled, this mechanism being such that the grinding wheel may be fed in either direction while the machine is running.

A further object is to provide means whereby the rapid adjustment of the grinding wheel may be made by hand when the main bearing supporting the grinding wheel and its parts is idle.

A further object is to provide very simple and effective means whereby the grinding wheel may be adjusted while the spindle is rotating and while the spindle and grinding wheel are moving in a circular path, and whereby the grinding wheel and spindle may be fed in one direction or the other as desired.

And a further object is to provide means whereby the engagement of the driving worm with the worm gear may be adjusted to take up wear.

The invention consists in the details of construction and in the combination and arrangement of the several parts of my improved grinding machine whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the

better understood, I will now proceed to describe the same with reference to the accompanying drawings, wherein:

Figure 1 is a side elevation of an internal grinding machine constructed in accordance with my invention;

Figure 2 is a rear end elevation of the machine;

Figure 3 is a fragmentary vertical sectional view through the housing 10 and a portion of the base B taken on the line 3-3 of Figure 4;

Figure 4 is a detail rear elevation of the housing and bearings for the spindle;

Figure 5 is a fragmentary vertical sectional view through the rear end of the spindle and the bearings therefor showing the water ducts in section;

Figure 6 is a fragmentary longitudinal sectional view through the forward end of the spindle and the grinding wheel mounted thereon;

Figure 7 is a section on the line 7-7 of Figure 3 but showing the spindle in its lowermost position;

Figure 8 is a sectional view on the line 8-8 of Figure 7;

Figure 9 is a top plan view of the construction shown in Figure 7;

Figure 10 is a sectional view on the line 10-10 of Figure 9; and

Figure 11 is a fragmentary elevation looking from the rear of the feeding mechanism illustrated in Figure 7.

Referring to the drawings, and particularly to Figure 1, it will be seen that my mechanism as a whole includes the base A, a supporting column B wherein the spindle and spindle operating mechanism is supported, as will be later described, and a work support C which is mounted for longitudinal movement upon the power driven table D and consists of a plurality of relatively adjustable sections whereby the work may be shifted longitudinally of the table, transversely of the table, or rotated relative to the longitudinal axis of the table, and whereby the work may be held at any desired elevation. This mechanism, which I have designated generally A, B, C and D, forms no part of my invention, my present invention residing in the means whereby the

spindle carrying the grinding head is rotated and given a bodily movement around a central axis.

Referring to Figure 3, it will be seen that the column B has rotatively mounted there-in an approximately cylindrical carrier 10 which is provided intermediate its ends with the gear 11. This cylindrical carrier is provided at its ends with the inwardly directed, annular flanges 12 and 13 forming bearings for a spindle housing 14. This member 10 may be rotated by any suitable mechanism, but I have illustrated for this purpose a shaft 15 carrying a pinion or gear wheel engaging the gear wheel 11 and driven by a belt or sprocket chain 16, in turn operating over a belt wheel or sprocket wheel 17 carried upon the shaft 18 driven by a sprocket chain 19 from a sprocket wheel 20 on a motor shaft 21, the motor being designated 22. I do not wish to be limited, however, to the particular means for driving the member 10. This member is entirely enclosed within the housing formed by the column B and the cap B' thereof.

Disposed within the cylindrical carrier 10, as previously stated, is the spindle housing 14, which is annular in cross section, and this spindle housing 14, as indicated clearly in Figure 4, is eccentrically disposed with relation to the carrier 10 so that as this carrier 10 rotates in the direction of the arrow in Figure 4, the spindle housing will be carried bodily around the axis a, and it will be seen from Figure 3 that this spindle housing 14 has a passage 23 which is eccentric to the periphery of the spindle housing. Extending through this passage 23 is a spindle, designated generally 24, and which, as illustrated, is composed of two sections coupled, as at 49, for unitary rotation. This spindle is considerably longer than the spindle housing and projects beyond the spindle housing both at its forward and rear ends. Extending from the body of the spindle housing 14 is the front spindle housing 25 within which the forward portion of the spindle 24 is disposed and in which it is rotatably mounted. The forward end of the spindle 24 is mounted in exteriorly conical bearings 26 (see Figure 6), while that portion of the spindle coincident with the rear end of the forward spindle housing 25 is mounted in bearings 27 which are likewise conical.

The forward end of the housing 25 is screw-threaded, and engaged therewith is a collar 28 having an annular flange 29 extending over the end of the bearing 26, and by rotating this collar it is obvious that the wear on the bearing may be taken up. The spindle is reduced at this point, as at 30, and surrounding the reduced portion of this spindle and bearing against the forward flange 29 of collar 28 and extending over the

forward portion of this collar 28 is a dust cap 31 which rotates with the spindle 24.

Surrounding the body of the dust cap 31 is the grinding wheel 32 which may be an emery grinding wheel or carborundum grinding wheel, or a grinding wheel of any suitable character, the face of this grinding wheel being cut out at its center, as at 33. The extremity of the reduced portion 30 of the spindle 24 is screw-threaded, and engaging this screw-threaded portion is a nut 34. The spindle has a longitudinally extending bore 37 by which water may be supplied to the grinding wheel, and particularly in the manner and for the purpose set forth in my pending application, Serial No. 401,988, Patent No. 1,396,123, of which the present application is a division.

The rear end of the spindle 24 projects beyond the cylindrical housing 14. This housing 14 is cut out at its rear end to receive certain ball bearings, as will be later stated, and mounted upon the spindle 24 are the two connected driving pulleys 38 and 39 which are keyed or otherwise connected to the spindle 24 to rotate therewith. The ball bearing for the support of the rear end of the spindle may be of any suitable construction, and, as illustrated in Figure 5, comprises an inner member 40, the outer annular member 41, and intermediate anti-friction elements, such as anti-friction balls. This bearing is held in place by means of a jam nut 42 exteriorly threaded to engage the interior threads, on the recess formed in the rear end of the housing 14, as most clearly illustrated in Figure 5.

The rear end of the housing 14 is exteriorly screw-threaded for engagement by the nuts 4 and 3, whereby the housing is held in proper relation to the rotatable carrier 10, which has an annular plate 10^a attached to it by screws and against which the nuts 43 bear, the forward end of the housing section 14 having a flange 44 which bears against the split ring 43^a. The nuts 43 pull the spindle housing 14 against the split ring 43^a on the forward end of the spindle housing and push the rear split ring 43^b against the end flange plate 10^a. This insures perfect bearing at all times. Thus, the housing section 14 is supported for relatively rotary movement within the rotatable carrier 10 and the spindle is supported for rotation around its own axis within the housings 14 and 25.

In order to provide means whereby the grinding wheel may be adjusted toward or from the axis a around which the grinding wheel rotates to thereby finely adjust the depth of cut, I provide means whereby the spindle housing 14 and the front spindle housing 25 may be axially rotated. To this end, I mount upon the forward end of the carrier 10 an approximately annular plate 130

68 (see Figures 3 and 7) having an eccentrically disposed, circular opening 69 which fits over the flange 44 of housing 14 and which is provided with a marginal flange 70 fitting over an annular rabbet or recess formed in the forward end of the carrier 10.

This plate 68 carries at one point on its periphery a bearing bracket 71 supporting a shaft 72 which, at its rear end, carries a ratchet wheel 73, having radially projecting teeth. The opposite end of this shaft 72 carries a worm 74. This worm meshes with a worm wheel 75 loosely mounted on a shaft 76 carried in bearings 77 on the plate 68. One face of the worm wheel 75 carries upon it the clutch teeth 78, and coacting with these clutch teeth is a clutch member 79 mounted upon the shaft 76. A coiled compression spring 80 bears against one of the bearing 20 lugs 77 and against a collar 81 carried by the shaft 76 so that normally the clutch member 79 is urged into engagement with the clutch teeth 78 and thus the worm wheel 75 is clutched to the shaft 76. This shaft 25 between the bearing members 77 carries a worm 82, and at one extremity carries a knurled hand wheel or knob 83.

The plate 68 is mounted upon the carrier 10, and surrounding the extremity of the 30 spindle housing 14 is a worm gear wheel 84. This worm gear wheel 84 has its central opening concentric to the axis of the worm gear. This worm gear wheel is attached to the housing member 14 by screws 85. Worm 35 82 is keyed to shaft 76 by key 82a.

Mounted upon the housing section B' and, therefore, held stationary relative to the rotation of plate 68 and bracket 71 is an upwardly projecting bracket 86 having two 40 passages for the two longitudinally shiftable pins 87 and 88 (see Figures 9 and 10). The walls of the pin passages in the bracket 86 are slotted, as at 89, and ears 90 project from the pins 87 and 88 and extend into said slots.

The rear ends of the pins 87 and 88 are headed, as at 91, and springs 92 urge these pins rearward, that is, retract the pins. Mounted upon these pins are the triangular cams 108 and 109. The cam 108 has its 50 angular face, that is, the hypotenuse of the triangle, facing downwardly and toward the left in Figure 7. The other cam 109 has its inclined face or hypotenuse facing upwardly and extending downward and toward the left in Figure 7. Either of these cams is adapted to be manually projected into active position by pressing on the appropriate knob 91, but is normally retracted by the spring 92 and held thereby out of active position.

60 Mounted upon the shaft 72 rearward of the ratchet wheel 73 is a pawl carrying lever 110. This lever is rockable with relation to the shaft 72 and is held in place by the journal screw 111. The ratchet wheel 73 is, of course, fast on shaft 72. This lever projects

laterally from its axis in one direction to form the relatively long arm of the lever, and the outer end of this arm is provided with a rearwardly projecting pin 112 carrying a roller 113, as shown best in Figure 11, 70 which roller is adapted, as the plate 68 is rotated, to engage with whichever cam 108 or 109 is projected.

This lever 110 carries upon it the substantially triangular pawl 114, which is triangular in form to provide the oppositely projecting teeth 115 and 116 engageable with the ratchet wheel 73. The apex of the triangular pawl is engaged by a spring pressed pin 117 urged toward the pawl by a spring 80 118, as shown in Figure 9. The extremity of this pin 117 is rounded and bears against the rounded apex of the pawl and yieldingly holds the pawl in one or the other of its active positions. The opposite end-face of 85 the lever 110 is formed with a V-notch 119, and disposed on a bracket or lug 120 projecting from the bearing member 71 is a pin 121 urged toward the notch 119 of the lever by means of a spring 122.

Extending from the bracket 71 and specifically from the bearing portion of this bracket is a lug or extension 123 having a rearwardly projecting lug 124 constituting a stop. The base of this bracket 71 is also 95 formed with an outwardly projecting lug 125 constituting a stop. The pawl 114 is adapted to engage with one or the other of the stops. Thus, for instance, referring to Figure 11, when the pawl carrying lever 110 moves 100 downward beyond a certain point, the tooth 116 of the pawl 114 will strike the stop 125 and this will shift the pawl 114 so as to bring its tooth 116 in engagement with the teeth of the ratchet wheel 73 and bring the tooth 115 out of engagement with the teeth of the ratchet wheel 73. On the other hand, if the tooth 116 is engaged with the ratchet wheel 73, then upon an upward movement of the roller carrying end of the lever 114 beyond a certain point, the tooth 115 will 105 strike the stop 124 and the position of the pawl will be reversed.

It will be seen that when the operator presses upon one or the other of the pins 87 or 88, the corresponding cam 108 or 109 will be projected into the line of body rotation of roller 113, this roller being carried around with the plate 68 and with the main bearing. The roller strikes and glides upon the inclined face of the cam, and thus oscillates pawl-carrying lever 110 and the pawl 114 will carry the ratchet wheel around in one direction, thus giving a partial revolution to 120 the worm 74. This, being engaged with worm gear 75, revolves the worm gear, which in turn revolves the worm 82 and the worm gear wheel 84, thus making an adjustment of the emery wheel cut by moving the worm gear wheel 84 which is attached eccentrically 125 130

to the rear spindle housing, said housing supporting the front spindle housing 25. After the roller 112 has traveled over the cam, as for instance the cam 108, and has moved off this cam, the lever 110 is brought back to its neutral position by spring plunger 121.

When a reverse adjustment of the feed is required, the operator forces out the other cam, for instance cam 109, and the roller 10 113 will move over the upper face of this cam, thus shifting the lever in the opposite direction and thus feeding the ratchet wheel in the opposite direction and feeding the spindle oppositely. The lever 110 which has 15 been shifted to the proper position to cooperate with the cam 108 will, of course, need to be shifted to a reverse position in order to operate the cam 109, and when the operator puts the cam 109 into position to 20 engage the roller 113, the tooth 115 of pawl 114 will strike the stop 124, thus throwing the pawl into opposite center of the spring plunger 117 and thus cause the tooth 116 to engage the ratchet teeth. Thus, the pawl 25 is kept in one position or the other until the opposite cam is projected. Of course, as soon as pressure is released from the press buttons 91, either cam will be retracted away from the line of rotation of the roller 30 113 and the feed will stop.

For rapid adjustment of the wheel, the operator presses upon the knob or wheel 83, which disengages the clutch member 79, thereby releasing all the automatic feed 35 mechanism and then by rotating the wheel or knob 83, a direct and rapid adjustment may be secured in the manner above indicated through the action of the worm 82 on the worm wheel 84. Upon the release of 40 the knob or wheel 83, the clutch member 79 is automatically reengaged with the worm gear wheel 75.

It is desirable to provide means whereby 45 the engagement between the worm gear 84 and the worm 82 may be adjusted to take up wear. To this end, the front plate 68 is attached to the carrier or main bearing 10 by means of cap screws 93 passing through slots 94 in the plate 68. Attached 50 to the plate 68 by means of a screw 95 is an eye-bolt or adjusting screw 96, through the eye of which the screw 95 passes, the shank being threaded. This screw-threaded shank 96 passes through a stud 97 which is 55 screwed in the end of the carrier or main bearing 10. The screw 96, of course, passes loosely through the perforation in the stud 97 and on each side of this stud are disposed the knurled nuts 98 and 99. By releasing 60 the cap screws 93, the front plate 68 can be drawn around circumferentially by turning the knurled nut 99, which action draws the worm 82 into deeper mesh with the worm gear 84. After the desired adjustment 65 has been made, the parts are locked in

their adjusted position by the lock nut 98 and the cap screws 93. It will be noted that the pivotal axis of the bearing plate 68 is equi-distant from the axis of rotation of the housing 10 and the axis of rotation of 70 the spindle 24, thus permitting the axis of the spindle 24 to be located in coincidence with the axis of the housing.

The work carriage C may be of any suitable design or character and is provided 75 with means whereby it may be longitudinally shifted toward or from the grinding wheel and the work raised or lowered, or the work turned into any desired angle with the axis of the grinding wheel. Of course, 80 it will be understood that other work supporting means may be used in connection with the movable feed table D, and that the various kinds of work, as for instance, rods, pins, cylinders, pistons, etc. may be ground, 85 and that where rods or pins are to be ground, the rod or pin or other work will be rotated and carrier 10 will be idle while spindle 24 will rotate around the axis *a*, and that the same is true of grinding the 90 exterior of a cylinder or piston, but that when interior work is to be ground, the grinding wheel is disposed within the hollow article and revolves around the central axis *a*. 95

A lever 106 (see Figure 1) is used for shifting the clutch (not shown) which allows for throwing idle the main bearing 10, or for causing power to be transmitted to this main bearing 10 or carrier. The throwing of this main bearing 10 idle does not, of course, stop the revolution of the spindle carrying the emery wheel. The lever 107 is used for changing the speeds of the movable base D. The clutch mechanism controlled 100 by the lever 106 and the means for securing variable speeds of the table D have not been illustrated, as it is not believed necessary, as these parts are more or less old and well known. 110

The general operation of this mechanism will be obvious from what has gone before. The article to be ground or operated on is supported on the movable work support and adjusted to the proper position, and the carrier or main bearing 10 is then rotated through the gear 11 and at the same time the spindle is rotated through the pulleys 38 or 39. By the means heretofore described, the spindle and grinding wheel may be 115 bodily shifted radially outward or inward, as desired, either automatically by forcing in one or the other of the pins 87 or 88, or by disconnecting the clutch 79 the feed may be rapidly controlled by means of the wheel 120 83. The feeding means which I have devised provides for an extremely fine adjustment of the feed capable of feeding the cut in fractions of thousandths of an inch while 125 the machine is running. 130

While I have illustrated a construction which has been found thoroughly effective for the purpose intended, yet it will be obvious that many modifications might be made in the details of construction and arrangement of parts without departing from the spirit of the invention.

It will be understood that the outward feed of the grinding wheel is necessary in grinding internal surfaces and that the mechanism for inwardly adjusting the grinding wheel is especially needed for grinding external cylindrical surfaces.

I claim:

1. A grinding machine including a support, a cylindrical carrier journaled therein and having an eccentric passage extending through it, a cylindrical bearing journaled in said passage, a spindle journaled eccentrically within said bearing and carrying a grinding-wheel, a plate affixed to one end of said carrier, said affixing means embodying two arcuate slots in the plate and also an opening, clamping bolts extending through said slots and anchored in the carrier, a lug affixed to the carrier and extending through said opening, screw-bolt-means connecting said lug to said plate for the purpose of rotatively adjusting the same when the clamp bolts are loosened, means for rotatively adjusting the bearing embodying a worm-gear affixed to the bearing, and a shaft journaled on said plate and carrying a worm meshing with said worm-gear.

2. A grinding machine including a rotatable element constituting a carrier having a passage extending therethrough eccentric to the axis of rotation of the carrier, a spindle bearing mounted in said passage for rotation with relation thereto, a spindle rotatably mounted in said spindle bearing and carrying a grinding wheel, and means for independently rotating the spindle and the carrier, means being also provided for automatically bodily moving the spindle bearing inwardly or outwardly, this last-named means embracing two reversed manually-set elements and a co-acting reversible pawl and ratchet mechanism.

3. A grinding machine including a rotatable carrier having a passage extending therethrough eccentric to the axis of rotation of the carrier, an independently rotatable spindle mounted in said passage and carrying a grinding wheel, means for rotating the spindle, and means for rotating the carrier, means being also provided for bodily moving the spindle inwardly or outwardly embodying two independent manually-set cam elements and a pawl and ratchet mechanism co-acting therewith.

4. A grinding machine including a rotatable carrier having a passage extending therethrough eccentric to the axis of rota-

tion of the carrier, a tubular bearing mounted in said passage for rotation with relation to the carrier, a spindle rotatably mounted within the bearing and eccentric thereto, means for rotating the carrier, means for 70 rotating the spindle, and manually controlled means for rotating the bearing within the carrier to thereby control the eccentricity of the spindle relative to the carrier, means being also provided for bodily shifting the spindle inwardly or outwardly embodying a reversible pawl and ratchet mechanism bodily rotatable, a pair of co-acting cam devices mounted on a stationary support, and devices whereby either one of 80 these cam devices may be brought into co-action with the reversible pawl and ratchet means.

5. A grinding machine including a rotatable carrier and having a passage extending 85 therethrough eccentric to the axis of rotation of the carrier, a tubular bearing mounted in said passage for rotation with relation to the carrier, a spindle rotatably mounted within the bearing and eccentric 90 thereto, means for rotating the carrier, means for rotating the spindle, manually controlled means for rotating the bearing within the carrier to thereby control the eccentricity of the spindle relative to the 95 carrier and including means for rotating the bearing embodying members mounted upon the bearing for rotation therewith, and a pair of relatively fixed members adapted to engage with the reversely-arranged members carried on the bearing. 100

6. A grinding machine including a rotatable carrier, a fixed element within which the carrier rotates, said carrier having a longitudinally extending passage eccentric 105 to the axis of rotation of the carrier, a bearing rotatably mounted within the carrier and having a passage extending therethrough eccentric to the axis of the bearing, a rotatable spindle carried within said bearing, means for independently rotating the carrier and said spindle, and means for 110 rotatively adjusting the bearing to thereby adjust the spindle nearer to or further from the axis of rotation of the carrier including gears, one mounted on the bearing and one mounted on the carrier, and reversible ratchet means for operating said gearing. 115

7. A grinding machine including a rotatable carrier, a fixed element within which the carrier rotates, said carrier having a longitudinally extending passage eccentric to the axis of rotation of the carrier, a bearing rotatably mounted within the carrier and having a passage extending therethrough eccentric to the axis of the bearing, a rotatable spindle carried within said bearing, means for independently rotating the carrier and said spindle, means for rotating the bearing to thereby adjust the spindle nearer 120 125 130

to or further from the axis of rotation of the carrier including a shaft mounted upon and carried by the carrier and having a worm, a worm wheel mounted upon the bearing and with which said worm engages, a worm gear wheel mounted upon the shaft, a worm engaging said worm gear wheel and mounted upon the carrier, a feed wheel operatively engaged with said last named 5 worm to rotate it and mounted upon and rotatable with the carrier, and members mounted upon the fixed element and independently projectable into the path of movement of the feed wheel, one of said 10 members being disposed on one side of the axis of the feed wheel and the other member on the opposite side of the axis whereby to cause a rotation of the feed wheel through a predetermined angular distance upon the 15 engagement of the feed wheel with one or the other of said members, said members being normally retracted but being manually projectable into the path of movement of the feed wheel.

20 8. A grinding machine including a rotatable carrier, a fixed element within which the carrier rotates, said carrier having a longitudinally extending passage eccentric to the axis of rotation of the carrier, a bearing rotatably mounted within the carrier and having a passage extending therethrough eccentric to the axis of the bearing, a rotatable spindle carried within said bearing, means for independently rotating the carrier and said spindle, means for rotating the bearing to thereby adjust the spindle nearer to or further from the axis of rotation of the carrier, a shaft mounted upon the end face of the carrier and carrying a 25 worm, a worm gear wheel mounted upon the adjacent end face of the bearing and carrying a worm gear wheel with which the worm engages, a worm gear wheel loosely mounted upon said shaft, a clutch operative 30 to engage or disengage the worm wheel with the shaft, a shaft mounted upon the carrier at right angles to the first named shaft and carrying a worm engaging said last named worm gear wheel, a feed wheel mounted upon said last named shaft, and a pair of 35 spring retracted cams mounted upon the fixed element and each independently shiftable into the path of movement of the feed wheel, one of said cams being disposed on one side of the path of movement of the axis of the feed wheel and the other on the opposite side thereof whereby the feed wheel may be rotated in one direction or the other one step upon each complete rotation of the carrier.

40 9. A grinding mechanism including a rotatable carrier, a fixed element in which the rotatable carrier is mounted, said carrier having a passage extending therethrough eccentric to the axis of rotation of the carrier, a bearing mounted within said passage for rotation therein, a spindle rotatably mounted within the bearing eccentrically to the axis thereof and carrying a grinding wheel, a worm shaft mounted upon one end of the carrier for longitudinal movement, a worm thereon, a worm gear wheel mounted upon the bearing with which said worm engages, a worm gear wheel loosely mounted upon the shaft, a clutch member mounted upon the shaft and engageable with the last named gear wheel, a spring urging the shaft in a direction to engage the clutch with the worm gear wheel, means on the shaft for manually rotating it or longitudinally shifting it to disengage the clutch from the worm gear wheel, a shaft mounted upon the carrier and extending at an angle to the first named shaft and carrying a worm engaging with the last named worm gear wheel, and means for causing a fractional rotation of the last named shaft upon each complete rotation of the carrier.

45 10. A grinding machine including a rotatable carrier, a fixed element within which

the carrier, a bearing mounted within said passage for rotation therein, a spindle rotatably mounted within the bearing eccentrically to the axis thereof and carrying a grinding wheel, a worm shaft mounted upon one end of the carrier and extending tangentially to the bearing, a worm gear carried by the bearing and engaged by the worm on said shaft, and means for taking up wear between the worm and said worm gear wheel embodying devices for bodily rotatively adjusting the worm with respect to said carrier.

11. A grinding mechanism including a rotatable carrier, a fixed element in which the rotatable carrier is mounted, said carrier having a passage extending therethrough eccentric to the axis of rotation of the carrier, a bearing mounted within said passage for rotation therein, a spindle rotatably mounted within the bearing eccentrically to the axis thereof and carrying a grinding wheel, a plate mounted upon one end of the carrier for shifting movement around the axis of the carrier, a worm shaft mounted upon said plate and carrying a worm, a worm gear wheel mounted upon the adjacent extremity of the bearing and with which said worm engages, means for shifting said plate rotatively with relation to the carrier comprising a pin mounted on the plate, an eye-bolt engaged with said pin and having a screw-threaded shank, a lug on the carrier through which the screw-threaded shank passes, and adjusting nuts engaging the shank and said lug.

12. A grinding mechanism including a rotatable carrier, a fixed element in which the rotatable carrier is mounted, said carrier having a passage extending therethrough eccentric to the axis of rotation of the carrier, a bearing mounted within said passage for rotation therein, a spindle rotatably mounted within the bearing eccentrically to the axis thereof and carrying a grinding wheel, a worm shaft mounted upon one end of the carrier for longitudinal movement, a worm thereon, a worm gear wheel mounted upon the bearing with which said worm engages, a worm gear wheel loosely mounted upon the shaft, a clutch member mounted upon the shaft and engageable with the last named gear wheel, a spring urging the shaft in a direction to engage the clutch with the worm gear wheel, means on the shaft for manually rotating it or longitudinally shifting it to disengage the clutch from the worm gear wheel, a shaft mounted upon the carrier and extending at an angle to the first named shaft and carrying a worm engaging with the last named worm gear wheel, and means for causing a fractional rotation of the last named shaft upon each complete rotation of the carrier.

13. A grinding machine including a rotatable carrier, a fixed element within which

- the carrier rotates, said carrier having a longitudinally extending passage eccentric to the axis of rotation of the carrier, a bearing rotatably mounted within the carrier and having a passage extending therethrough eccentric to the axis of the bearing, a rotatable spindle carried within said bearing, means for independently rotating the carrier and said spindle, means for rotating 50 the bearing to thereby adjust the spindle nearer to or further from the axis of rotation of the carrier including a shaft mounted upon the end face of the carrier and carrying a worm, a worm gear wheel mounted 55 upon the adjacent end face of the bearing with which said worm engages, a worm gear wheel loosely mounted upon the shaft, a clutch operative to engage or disengage the last named worm gear wheel with or from 60 said shaft, a shaft mounted upon the carrier at right angles to the first named shaft and carrying a worm engaging said last named worm gear wheel, a ratchet wheel 65 mounted upon the last named shaft, a lever having a double pawl engageable with the ratchet wheel, said lever carrying a roller, spring actuated means holding the lever in a neutral position with relation to the ratchet wheel, a pair of spring retracted 70 members mounted on the fixed element and each having a cam, the cam having oppositely inclined cam faces, each cam being independently shiftable to carry its cam face into the path of movement of the roller on 75 said lever, one of said cams being disposed on one side of the path of movement of the roller and the other on the opposite side thereof whereby the ratchet wheel may be rotated in one direction or the other one step 80 upon each complete rotation of the carrier.
13. A grinding machine including a rotatable carrier, a fixed element within which the carrier rotates, said carrier having a longitudinally extending passage eccentric 85 to the axis of rotation of the carrier, a bearing rotatably mounted within the carrier and having a passage extending therethrough eccentric to the axis of the bearing, a rotatable spindle carried within said bearing, means for independently rotating the carrier and said spindle, means for rotating the bearing to thereby adjust the spindle nearer to or further from the axis of rotation of the carrier including a shaft mounted upon the end face of the carrier and carrying a worm, a worm gear wheel mounted upon the adjacent end face of the bearing with which said worm engages, a worm gear wheel loosely mounted upon the shaft, a clutch operative to engage or disengage the last named worm gear wheel with or from said shaft, a shaft mounted upon the carrier at right angles to the first named shaft and carrying a worm engaging said last named worm gear wheel, a ratchet wheel mounted on the shaft, a lever loosely mounted upon the shaft of the ratchet wheel and carrying a roller at one end, the opposite end of the lever being reentrantly angled, a spring actuated pin bearing against the apex of said reentrant angle and resisting oscillation of the lever, a pawl mounted upon the lever and triangular in form to provide two teeth, either of which is engageable with the ratchet wheel, resilient means yieldingly holding one or the other of said teeth in engagement with the ratchet wheel, fixed stops mounted above and below the pawl and with which the pawl is engageable to shift the pawl to carry one or the other of its teeth into engagement with the ratchet wheel, and cams independently movable into the path of said roller, said cams having oppositely inclined faces and acting to shift the roller in one direction or the other upon each rotation of the carrier.
